The ornamental design for a timestamp holder, as shown and described.

DESCRIPTION

FIG. 1 is a perspective view of a timestamp holder according to the present invention;

FIG. 2 is a front view of the timestamp of FIG. 1;

FIG. 3 is a back view of the timestamp of FIG. 1;

FIG. 4 is a first side view of the timestamp of FIG. 1;

FIG. 5 is a second side view of the timestamp of FIG. 1;

FIG. 6 is a top view of the timestamp of FIG. 1; and,

FIG. 7 is a bottom view of the timestamp of FIG. 1.
